UNITED STATES PATENT OFFICE.

FRED O. LINGENFELDER, OF LINCOLN, NEBRASKA.

RACING TOY.

Application filed December 11, 1926. Serial No. 154,114.

This invention relates to an amusement device which is both entertaining and instructive as it cultivates the judgement, trains the eye and hand and enables one to 5 enjoy moments of relaxation.

The invention provides in effect a toy embodying a speedway, electrically propelled cars thereon, means for varying the current supplied to the cars to drive them fast or 10 slow as desired, and switch means for diverting the cars from one track or course to another to add to the interest and pleasure.

The invention contemplates a speedway embodying a plurality of courses disposed in 15 parallel relation and including straightaway portions and return portions, the latter being foldable to reduce the length of the device and serving to connect the straightaway portions, which, for lightness, are separate 20 units spaced apart.

While the drawings illustrate a preferred embodiment of the invention, it is to be understood that in adapting the means to meet specific needs and requirements the design may be varied and such other changes 25 in the minor details of construction may be resorted to within the scope of the invention as claimed, without departing from the spirit thereof.

For a full understanding of the invention and the merits thereof reference is to be had to the following description and the drawings hereto attached, in which,

Figure 1 is a top plan view of a race toy 35 embodying the invention, the dotted lines indicating an adjusted position of the switches and one of the cars diverted from one course or track to another.

Figure 2 is an edge view, the dotted lines 40 showing the return portions of the speedway folded.

Figure 3 is a transverse sectional view on the line 3-3 of Figure 1, looking in the direction of the arrows.

Figure 4 is an enlarged detail sectional view on the line 4-4 of Figure 1.

Figure 5 is a detail sectional view of the means for mounting and operating the switches.

Figure 6 is a sectional view of a resistance

for varying the supply of current to a car to change its speed.

Figure 7 is a side view of a racing car, and Figure 8 is a view of the car as seen from the bottom side.

Corresponding and like parts are referred to in the following description and designated in the several views of the drawings by like reference characters.

The speedway usually consists of a board 60 and may be a flat body of any determinate material and comprises a middle straightaway portion and return ends, the latter being preferably hingedly connected to the middle portion to fold thereunder, as indicated by the dotted lines in Figure 2, thereby to admit of the length being materially reduced for handling and storing. In the preferable construction the middle portion of the speedway comprises similar 70 sections or parts 10 which are transversely spaced. The return end portions 11 are hingedly connected to the middle portions 10, as indicated most clearly at 12 in Figure 2. The return portions 11 are of semi-circular outline and are adapted to fold against the lower side of the middle portion, as indicated by the dotted lines in Figure 2. A plurality of courses, or tracks 13, 75 14 and 15 are provided upon the top side of the speedway and are parallel and separated by guards 16 which usually consist of ribs or strips, which may form a part of the body or attached thereto in any determinate way. Outer guards 17 prevent the 80 cars from leaving the speedway. A pair of metal strips 18 is provided for each course or track and constitutes conductors for supplying the electric current to the motors of the cars. To prevent buckling and warping 85 of the strips 18, their longitudinal edge portions are bent at a right angle, as indicated at 19, and are fitted in grooves formed in the speedway. The marginal flanges 19 also serve as retaining means for securing the 90 conducting strips to the body of the speedway since they are pressed into grooves formed therein, as indicated most clearly in Figure 4. The middle portion of each 95 course or track is formed with a groove in 100

which is pressed a retaining strip 20 which assists materially in securing the conducting strips 18. The conducting strips 18 form in effect rails for the several courses or tracks, 5 and current is supplied thereto from a suitable source by means of lead wires 21, a resistance 22, being interposed in the leads to step down the current and vary the supply to the cars, whereby the speed may be 10 regulated or changed at will to suit the fancy of the operator. Each resistance is provided with an operating lever 23 which may be manipulated to vary the current supply to each of the cars as required.

15 The guard 16 separating adjacent courses or tracks has a section 24 pivoted at one end and movable laterally to divert a car from one track to another, whereby to intensify the interest in the operation of the toy. By 20 regulating the supply of current to a car it may be speeded so as to pass another car in the race and by deftly manipulating the switch the car may be diverted from one track to the track containing the car which 25 has been passed so as to lead said car. The operator of the trailing car may switch it to another track and increase the speed by augmenting the current supplied thereto so as to pass the leading car under favorable conditions. It will thus be understood that the 30 arrangement is such as to admit of one car in the race passing another and being diverted to the same track containing the car which has been passed. An advantage results 35 from occupying the innermost course or track because it is the shortest, the several tracks increasing in length towards the outside, as will be readily appreciated. The switches 24 may be thrown inwardly or outwardly, as indicated by the dotted lines in Figure 1, and may be mounted in any preferred way and operated by any determinate mechanism.

40 As shown most clearly in Figures 4 and 45 5, a post 25 is mounted vertically in the body of the speed-way and the switch 24 is secured at one end to the upper end of the post, so as to turn therewith. An arm 26 fast to the lower end of the post 25 is 50 connected by means of a link 27 to a lever 28 mounted at one side of the speed-way. The bottom side of the body is recessed to receive the arm 26 and link 27, as shown 55 most clearly in Figure 4, so that the device may rest upon a table or analogous support. The switches 24 are differently positioned to avoid interference, as indicated 60 most clearly in Figure 1, and this admits of the lever 28 being correspondingly positioned for convenience of operation without interference.

65 The cars 29 may be of any design and each is supplied with an electric motor in a manner common in electrically operated toys. The current is supplied to the motor through

the wheels 30 and, as shown most clearly in Figure 4, the axle comprises sections which are electrically insulated, as indicated at 38, the current entering through one of the wheels and being grounded through the 70 other wheel, one of the conducting strips or rails 18 supplying the current and the companion conducting strip or rail grounding the same in a manner well understood in electric train toys. The racing car is 75 either of cast iron or pressed steel with iron wheels 30 made to represent automobile tires on disc wheels. The electric current enters through the wheels on one side, at 32, which have iron axles and iron bushings, and passes 80 through a motor 33, of approximately one three hundredth horse power, located under the hood of the car. The motor 33 drives the rear wheels through a shaft 34 and fibre ring gear 35 which also serves to separate the two rear axles 36. The current passes 85 through the opposite side of the car, at 37, where fibre bushings are provided for insulation. The front axles are electrically separated by a fibre coupling 38.

90 The resistance 22 is built either in one unit or combined so as to resemble three miniature automobile transmissions with gear shifting levers 23, one for each track. The lever 23 is located in the center of each resistance to operate as indicated by the dotted lines in Figure 6. Any number of lead wires 95 may be employed for supplying current from the resistance to the tracks. The speedway may comprise any desired number 100 of tracks, or courses, and the guards separating the tracks have the portions 24 pivoted and adapted to be separately operated from a side of the speedway by the levers 28 for diverting the racing cars 29 from one track to the other. The speedway may be lengthened and shortened, hence the intermediate straightaway portion may comprise 105 sections which may be added or removed as desired, the sections being retained in place by the hinges 12 or other suitable fastening means.

110 Having thus described the invention, I claim:

115 1. A speedway comprising a flat body provided with a plurality of paralleling courses or tracks which are separated by means of guards, and having a portion of the separating guard pivoted to provide a switch and means for operating the switch to divert a car from one track to another.

120 2. A speedway provided in its top side with pairs of narrow grooves and an intermediate wide groove, conducting strips or rails having marginal edge portions bent to provide flanges which are pressed into the narrow grooves of the body and a retaining strip pressed into the wide groove.

125 3. A speedway provided with a plurality 130 of courses or tracks, guards separating the

tracks, each of the guards having a pivoted section forming a switch, a post mounted in the speedway and having the switch fast at one end thereto, an arm projecting from the lower end of the post, a lever at one side of the speedway and a link connecting the lever with the said arm, whereby the switch may be operated.

4. A speedway for a racing toy comprising a plurality of tracks separated by guard rails and having a portion of the several guard rails pivoted to divert the cars from one track to the other.

In testimony whereof I affix my signature.

FRED. O. LINGENFELDER. [L.S.]
